UNITED STATES PATENT OFFICE.

EMIL KUPA, OF DUISBERG, GERMANY, ASSIGNOR TO THE BABCOCK & WILCOX COMPANY, OF BAYONNE, NEW JERSEY, A CORPORATION OF NEW JERSEY.

FURNACE.

Application filed November 6, 1922. Serial No. 599,480.

To all whom it may concern:

Be it known that I, EMIL KUPA, a citizen of the Republic of Germany, residing at Neudorferstrasse 32^a, Duisberg, Prussia, 5 Germany, have invented certain new and useful Improvements in Furnaces, of which the following is a specification.

My present invention relates to improvements in furnaces whereby fuel with a considerable moisture content may be economically burned. My invention will be best understood from the following description and the annexed drawing in which is shown a section of an illustrative embodiment of 15 my invention. In the illustrative form, 10 is a combustion chamber beneath a boiler having tubes 11 and provided with a chain grate 12 of the usual type to which fuel is fed from a hopper 13, mechanism being provided, as is usual, to move the chain so that the upper run thereof will carry the fuel from the hopper 13 toward the combustion chamber.

At the forward part of the chain grate is 25 a combustion arch 14 provided with a fuel gate 15 operable from the exterior of the furnace by a screw and nut arrangement 16. The usual fuel-feeding gate 17 is provided to limit the amount of fuel passing from the 30 hopper 13 to the grate.

Through the top of the combustion arch is an opening 18 connecting with a flue 19, the flue 19 communicating through an outlet 20 with the space above the fuel on the grate 12 held between the gates 15 and 17. The 35 outlet 20 may be provided with a damper 23.

Below this space is a draft box 21, at one side of which is connected an outlet pipe 22 which may be connected to any suitable 40 draft-inducing device, such as the combustion chamber 10, the chimney to which the waste gases from the combustion chamber is led, or a fan. On the links of the grate 12 are pivotally mounted dampers 23, which 45 dampers are arranged to slide on the side edges of the box 21, or to be otherwise so related thereto as to partially seal the space between the sides of the draft box 21 and the upper run of the grate.

50 When the illustrative device is in use, the suction through the pipe 22 draws hot furnace gases down through the portion of the fuel between the gates 15 and 17, such gases passing from the space beneath the combustion arch 14 through the opening 18 and the

ducts 19 and 20. The volume of these gases may be controlled by the damper 23. These hot gases serve to dry the fuel and to pre-heat it so that, as it passes beneath the gate 15 into the combustion space of the furnace, 60 it will ignite readily. The gate 15 may be regulated so that the fuel in the drying space between the gates 15 and 17 can be held back until it has become sufficiently dry for ignition, the amount of fuel being held in this 65 space being determined by the relative opening of the gates 17 and 15.

It will be seen that the gate or valve 15 serves to divide the grate surface into a combustion area and a drying area, the valve 15 70 forming one side of a drying chamber through which hot gases may be drawn to dry the fuel on the drying area of the grate. By regulating the height of the gate 15, the amount of dry fuel passing to the combustion 75 area may be controlled, while, at the same time, the contact between the bottom of the gate 15 and the fuel bed tends to prevent the interchange of air and gas currents between the combustion and drying areas of 80 the grate, though, of course, the seal between these two areas is not an absolute one.

It will be understood that the form which I have shown is merely illustrative, and that the embodiments may be varied over wide 85 limits.

I claim:

1. In a furnace, a grate, fuel-feeding means therefor, including a fuel-regulating valve, a fuel-retarding valve spaced from 90 the regulating valve, and means to pass heated gases from the combustion chamber of the furnace through the fuel between the valves.

2. In a furnace, a grate, a pair of valves spaced apart along the front end of the grate to form a drying chamber therebetween and arranged to permit a regulated amount of fuel to pass to the combustion portion of the grate, and means to pass 100 heated furnace gases through the fuel in said chamber.

3. In a furnace, a grate, a pair of valves spaced apart along the front end of the grate to form a drying chamber therebetween and arranged to permit a regulated amount of fuel to pass to the combustion portion of the grate, the valve nearest said combustion portion of the grate being arranged to retard the fuel to hold it in said 110

- drying chamber, and means to pass heated furnace gases through the fuel in said chamber.
4. In a furnace, a grate having a fuel-drying area and a fuel-combustion area, said grate being arranged to cause the fuel to pass from the drying area to the combustion area, a valve to regulate the passage of the fuel from the drying area 10 to the combustion area, and means to pass heated furnace gases through the fuel on said drying area.
5. In a furnace, a grate, fuel-feeding means therefor, including a fuel-regulating valve, 15 a fuel-retarding valve spaced from the regulating valve, and means to pass heated gases from the combustion chamber of the furnace through the fuel between the valves and the portion of the grate on which such fuel is 20 supported.
6. In a furnace, a chain grate, means to feed fuel to one end thereof, a fuel-retarding gate spaced from the fuel-feeding means, and means to pass heated furnace gases 25 through the retarded fuel.
7. In a furnace, a chain grate, a fuel hopper, a fuel-feeding valve, a fuel-retarding valve spaced therefrom, each of said valves being adjustable, whereby different thicknesses of the fuel bed passing thereunder 30 may be determined, and means to pass heated gases from the combustion chamber of the furnace down through the fuel between the valves.
- 35 8. In a furnace, a chain grate, fuel-feeding means at one end thereof, including an adjustable fuel gate, a second adjustable gate spaced from the fuel gate to form a drying chamber therebetween, and means for passing heated furnace gases through the fuel in said chamber.
9. In a furnace, a chain grate, fuel-feeding means at one end thereof, including an adjustable fuel gate, a second adjustable gate 40 spaced from the fuel gate to form a drying chamber therebetween, and means to pass heated furnace gases downward through the portion of the grate beneath said drying chamber and the fuel thereon.
10. In a furnace, a chain grate, a combustion arch over a portion thereof, a fuel-retarding valve at the front of the arch, a fuel-feeding valve at the front of the grate and spaced from the fuel-retarding valve to 45 form a driving chamber therebetween, and means to draw heated gases from the space beneath the combustion arch downward through the fuel in said drying chamber.
11. In a furnace, a chain grate having a fuel-drying area and a fuel-combustion area, 50 a valve to regulate the flow of fuel from the drying area to the combustion area, and means to pass heated gases through the fuel on said drying area.
12. In a furnace, a grate having a fuel-drying area and a fuel-combustion area, a drying chamber above the fuel-drying area, a valve to regulate the flow of fuel from the drying area to the combustion area, and means for passing heated furnace gases in 55 regulated amounts through the fuel on said drying area.

EMIL KUPA.
